UNITED STATES PATENT OFFICE.

JAMES F. VICH, OF JACKSON, MINNESOTA.

FURNITURE-CASTER.

1,190,826.

Specification of Letters Patent. Patented July 11, 1916.

Application filed March 18, 1916. Serial No. 85,032.

To all whom it may concern:

Be it known that I, JAMES F. VICH, a citizen of the United States, residing at Jackson, in the county of Jackson, State of Minnesota, have invented a new and useful Furniture-Caster; and I do hereby declare the following to be a full, clear, and exact description of the invention, such as will enable others skilled in the art to which it appertains to make and use the same.

The present invention relates to certain new and useful improvements in furniture casters, and has for its object to provide a device of this character which embodies novel features of construction whereby it will roll easily upon a thick carpet and always move easily without binding or sticking.

Further objects of the invention are to provide a furniture caster of this character which is comparatively simple and inexpensive in its construction, which has all the advantages of a large roller without lifting the article of furniture an objectionable distance above the surface of the floor, which will roll easily at all times and upon all kinds of surfaces, and which has no delicate parts to break or get out of repair.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a furniture caster constructed in accordance with the invention, showing the same as applied to the leg of an article of furniture. Fig. 2 is an end elevation thereof. Fig. 3 is a vertical longitudinal sectional view through the same. Fig. 4 is a transverse horizontal sectional view showing a modified form of the invention.

Corresponding and like parts are referred to in the following description and indicated in all the views of the drawings by the same reference characters.

Referring to the drawings, the numeral 1 designates a fork which has the arms thereof curved laterally and downwardly, in the usual manner, the downturned arms of the fork having openings near their extremi-

ties to receive the shaft 2, while the base of the fork is secured to the lower end of a spindle 3. A bearing plate 4 is secured to the spindle 3 just above the base of the fork 60 1, said bearing plate being provided with an annular raceway to receive the balls 5. A sleeve 6 fits loosely over the spindle 3, the bore thereof having a diameter larger than that of the spindle 3. The lower end of 65 the sleeve 6 carries a bearing plate 7 which rests upon the balls 5 and co-operates therewith to center the lower end of the spindle 3 within the sleeve 6. The upper end of the sleeve 6 is provided with a spacing collar 70 8 which holds the spindle 3 properly spaced therein, while a nut 9 is threaded upon the upper extremity of the spindle to retain the bearing sleeve in position. This bearing sleeve 6 is applied to the article of furniture 75 in the usual manner, the spindle 3 being free to rotate therein and the balls 5 which are interposed between the bearing plates 4 and 7 receiving the thrust due to the weight of the article of furniture and preventing any binding as the spindle rotates within the bearing sleeve.

A small roller 10 is journaled upon the shaft 2 between the arms of the fork 1. The shaft 2 is preferably removable and, in the present instance, one end thereof is shown as provided with a head 2^a, while the opposite end thereof is formed with a lateral opening to receive a cotter-pin 11. The small roller 10 is arranged within a large 90 hollow roller 12, the sides of the hollow roller being formed with large openings 13 of such a size that the distance between the edges of the openings and the periphery of the roller is less than the radius of the small 95 roller 10.

Secured to the inner faces of the arms 1 of the fork are dust excluding plates 14 which fit against the sides of the large hollow roller 12 and are of a sufficient size to 100 extend over the large openings 13 and prevent dust and dirt from entering the same.

The furniture is supported by the small roller 10, and the large hollow roller 12 serves to provide a continuous metal track 105 upon which the small roller 10 rolls when the furniture is moved. The small roller thus travels at all times upon a hard smooth surface, while the large hollow roller 12 revolves upon the floor to provide a continuous track for the small roller. The large roller will move readily over a thick carpet 110

having a long pile, whereas the small roller could only be moved over such a carpet with extreme difficulty. With the present construction the small roller always rolls upon 5 a hard smooth surface, while the large roller which engages the floor is of such a size as to pass readily over any obstructions or move easily upon a carpet.

A slight modification is shown by Fig. 4, 10 in which the sides of the small roller 10 are provided with annular raceways to provide balls 15, said balls engaging the inner faces of the sides of the hollow roller 12 to eliminate the friction between the same and 15 prevent binding. Under some conditions such a construction would be very advantageous.

Having thus described the invention, what 20 I claim as new and desire to secure by Letters Patent, is:—

1. A furniture caster including a fork, a shaft connecting the arms of the fork, a small roller journaled upon the shaft, and a 25 large hollow roller inclosing the small roller, the sides of the large hollow roller being formed of openings of such a size that

the distance between the edges of the opening and the periphery of the roller is less than the radius of the small roller, the large roller providing a continuous track 30 upon which the small roller moves.

2. A furniture caster including a fork, a shaft connecting the arms of the fork, a small roller journaled upon the shaft, a large hollow roller inclosing the small roller 35 and having shaft receiving openings in the sides thereof of such a size that the distance between the edges of the openings and the periphery of the roller is less than the radius of the small roller, the large roller providing a continuous track upon which the small roller rolls, and dust excluding plates applied to the arms of the fork and fitting 40 against the sides of the large roller to close the openings in the sides thereof. 45

In testimony whereof I have signed my name to this specification in the presence of two subscribing witnesses.

JAMES F. VICH.
